J. H. Bryant.
Attorney.

UNITED STATES PATENT OFFICE.

MORRIS SUSSMAN, OF WHITE PLAINS, NEW YORK, ASSIGNOR TO B. TROHN INC., OF NEW ROCHELLE, NEW YORK, A CORPORATION OF NEW YORK.

GUTTER HANGER.

Application filed February 10, 1923. Serial No. 618,244.

This invention relates to certain new and useful improvements in gutter hangers and has for one of its objects to provide a hanger formed from a single blank or strip of material that is bent into the proper configuration with the adjacent ends thereof interlocked and having a supporting bracket therefor struck out from the strip.

Another object of the invention is to provide a gutter hanger wherein the same is formed from a single strip of material of a length substantially equal to the combined length of the cross and arched bars of the hanger with a supporting bracket for the hanger struck out from the hanger strip intermediate the sides and ends thereof providing a pair of spaced supporting bars in the arched portion of the hanger and an opening in the cross bar at the end thereof adjacent the edge of the roof, the formation of the bracket supporting the hanger in the manner herein stated permitting the formation of the bracket from the same strip of material from which the hanger is constructed.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a gutter hanger constructed in accordance with the present invention, a portion of a roof being illustrated by dotted lines, while the gutter associated with the hanger is shown in cross-section.

Figure 2 is a top plan view of the hanger showing a portion of a gutter supported therein,

Figure 3 is a detail sectional view taken on line III-III of Fig. 1 showing the reinforcing side flanges carried by the cross bar of the hanger and the spaced arched bars of the hanger formed by striking out the supporting bracket, and

Figure 4 is a fragmentary top plan view

partly in section of the hanger and gutter showing adjacent ends of the cross and arched bars spread apart or separated for wedging or binding engagement with the adjacent edge of the gutter.

The gutter hanger disclosed in this application is formed from a single strip of material of a length substantially equal to the arch bar or lower curved portion or bottom wall of a gutter and the distance between the upper edges thereof, a saving of material in the formation of the supporting bracket for the hanger being effected by striking out the supporting bracket from the strip at points intermediate the sides and ends thereof with the supporting bracket forming an integral part of the hanger. The single strip of material from which the hanger is constructed is bent to provide an upper cross bar 1 and a depending arched bar 2, the cross bar 1 extending between the upper edges of the gutter 3 while the lower arched bar 2 intimately engages and supports the gutter 3 as shown in Fig. 1. The opposite side edges of the cross bar 1 are bent at right angles to provide side reinforcing flanges 4 as clearly illustrated.

The adjacent free ends of the cross and arched bars are interlockingly connected, the free end of the cross bar being bent as at 5 and provided with a slotted opening 6, the bent end 5 engaging the rolled edge or bead 7 upon the outer edge of the gutter 3, while the free end of the arched bar 2 is bent as at 8 for engaging the lower edge of the bead 7 and carries a tongue 9 that is inserted through the slot 6 as shown in Figs. 1 and 2 for securing the gutter in the hanger.

The supporting bracket 10 is struck out from portions of the cross bar 1 and arched bar 2 forming spaced arched bar sections as shown in Fig. 3 and an opening in one end of the cross bar 1, the bracket 10 being anchored beneath the roof boards 11 as shown in Fig. 1 while the inner side edge of the hanger and gutter engage the side wall 12 of a building. The integrally connected ends 13 of the cross and arched bars are formed as shown in Figs. 1 and 2 for intimately engaging the adjacent edge of the gutter 3.

to form a binding or frictional engagement therebetween, the integral and interlocking connections between the cross and arched bars preventing shifting movement of the 5 gutter in the hanger.

As shown in Fig. 4, the manner of striking out the supporting brackets from the cross and arched bars provides spaced bar sections, and if desired, the cross bar sections 10 1 may be spread apart or separated to cause the ends 13 thereof at their point of integral connection with the arched bar 2 to more intimately or frictionally engage the gutter 3.

15 From the above detail description of the device, it is believed that the construction and operation as well as the method of forming the same will at once be apparent, it being noted that the hanger and supporting bracket therefor are formed from a single strip of material of a length substantially equal to the distance between the upper edges of a gutter and the length of the lower curved wall thereof, the supporting bracket 20 25 being struck out from the cross and arched bars of the hanger at points spaced from the sides and ends thereof resulting in a considerable saving of material when compared with the mounting of a separate and independent supporting bracket.

30 While there is herein shown and described the preferred embodiment of the present invention, it is nevertheless to be understood that minor changes may be made therein 35 without departing from the spirit and scope of the invention as claimed.

What is claimed as new is:—

1. A gutter hanger comprising cross and arch bars, and a supporting bracket for the 40 hanger struck-out from portions of the cross and arch bars.

45 2. In a gutter hanger wherein the same is formed of a single strip of material, a supporting bracket struck out from the hanger intermediate the sides and ends thereof and an interlocking connection between the ends of said hanger.

3. In a gutter hanger wherein the same is

formed of a single strip of material bent to form cross and arch bars for the hanger, 50 a hanger supporting bracket struck out from the hanger intermediate the sides and ends thereof and an interlocking connection between the adjacent ends of the cross and arched bars. 55

4. In a gutter hanger wherein the same is formed of a single strip of material bent to form cross and arch bars for the hanger, a hanger supporting bracket struck out from portions of the cross and arched bars, and 60 an interlocking connection between adjacent ends of the cross and arched bars.

5. In a gutter hanger wherein the same is formed of a single strip of material bent to form cross and arch bars for the hanger, a 65 hanger supporting bracket struck out from portions of the cross and arched bars, the struck-out portion in the arched bar extending over the major length thereof to provide spaced supporting bars, the struck-out 70 portion in the cross bar being located at the end thereof adjacent the roof edge, and an interlocking connection between adjacent ends of the cross and arched bars. 75

6. In a gutter hanger formed of a single 80 strip of material bent to form cross and arch bars, an integral angle flange at each side of the cross bar, and a supporting bracket for the hanger struck out from portions of the cross and arch bars intermediate 85 the sides and ends thereof.

7. In a gutter hanger formed of a single strip of material bent to form cross and arch bars, an integral angle flange at each side of the cross bar, and a supporting 90 bracket for the hanger struck out from portions of the cross and arch bars intermediate the sides and ends thereof, the formation of the bracket providing side portions on parts of the cross and arch bars adapted to be forcibly separated for frictionally engaging a trough.

In testimony whereof I affix my signature.

MORRIS SUSSMAN.
